ATTORNEY

UNITED STATES PATENT OFFICE.

KARL REZNICEK, OF NEW YORK, N. Y.

ROTARY NOZZLE.

1,368,055.

Specification of Letters Patent.

Patented Feb. 8, 1921.

Application filed May 28, 1920. Serial No. 384,988.

To all whom it may concern:

Be it known that I, KARL REZNICEK, a citizen of the United States, and a resident of New York city, in the county of Kings and 5 State of New York, have invented certain new and useful Improvements in Rotary Nozzles, of which the following is a specification.

This invention relates to rotatable distributing nozzles or distributor heads. Its 10 objects are to provide a nozzle of its type in which the valve for the water supply pipe is free from all liability to become stuck fast in consequence of corrosion and to reduce the number of and to simplify the 15 working parts. The type of rotary nozzle in which my invention is an improvement is shown in the Schmidt Patent No. 885,869 of April 28, 1908, and in the older and well-known rotary globular head with projecting 20 outlets which have been marketed for many years past under the name of Bresnan's distributing or cellar nozzle, and extensively used by fire departments. It is shown 25 on page 74 of the trade catalogue of the Woodhouse Manufacturing Company, of New York city, edition of July 1, 1918.

In the accompanying drawings forming 30 a part hereof, and illustrating my invention:

Figure 1 is an under plan view.

Fig. 2 is a vertical central section at line 2—2 of Fig. 1.

Fig. 3 is a transverse section of line 3—3 35 of Fig. 2 of my improved rotary distributing nozzle.

Fig. 4 is an elevational view of the distributor nozzle looking at a side of the locking wing carrying bracket.

40 In that form of the invention now set forth, the chambered, rotary, distributing nozzle 1 with its horizontal outlets 2 spaced about 90 degrees apart around its horizontal diametric portion is formed at its upper end 45 with a round depression to form the flange 3 and interior horizontal rib 4 around the center bore 5 which opens upwardly into the space within the flange 3 and which opens downwardly into the lower chamber 6 50 of the globular nozzle or head; the wall of this chamber being shown formed with water escape holes 7, below the series of outlets 2. The interior upper margin of the flange 3 is threaded for reception of a 55 ball retaining ring 9 through the bore of which the under end of a water supply pipe

coupling 10 passes, the lower end portion of the coupling having an exterior ball supporting flange 11 on the upper side of which the anti-friction balls 12 are mounted. The 60 under side of this ball supporting flange rests on the rib 4 and the ball retaining ring 9 which is exteriorly threaded and screws into the upper interiorly threaded portion of the flange 3 and has its under side 65 opposed to the balls mounted on the flange 11. Thus the head or nozzle is made rotary on the coupling, the upper end of which is shown threaded at 12 for connection with a conduit forming part of a water supply 70 system.

The under side of the coupling 10 is formed with a downwardly projecting annular shoulder 14 the under surface of which is horizontal and forms a valve seat, 75 against which a valve packing 15 of yielding material and contained in the cupped valve head 16 of the upstanding valve for the under end of the coupling 10 is held in contact for tightly closing the coupling 80 and preventing access of water to the chamber of the head. The valve head 16 is of less diameter than the interior diameter of the center bore 5 bounded by the interiorly projecting horizontal rib 4 and is inclosed by 85 the interior wall 17 of the rib which is wholly out of contact with the valve head by a considerable clearance 19 that is wide enough to prevent the rib wall and the valve head from becoming stuck together by corrosion of the opposed metal. The rib 4 is formed with openings 18 each putting the chamber of the head into communication with an outlet 2.

The valve stem 20 for the valve head extends downwardly through the chamber 6 and is therein out of contact with all parts to which it could become stuck by corrosion. The stem is formed with lengthwise extending ribs 21, the stem being of reduced cross-sectional area between the ribs. The foot of the valve stem is entrant in, and passes downwardly through the center hole 22 of the nut head 23 of an upstanding bracket 24; the head 23 of which is exteriorly threaded 100 at 25 for connection with the interiorly threaded bottom opening of the head, the lower end portion of which has its wall appropriately thickened at 26 to permit the screwing of the bracket nut head into it, and 110 for formation of a hole for a set screw 27 by means of which the bracket is kept fixed to

the head. The bracket carries a collapsible valve locking device comprising a pair of supplementary wings 28 whose outer ends are connected by fusible metal 29, each wing having a bearing 30 at its head end and the two bearings 30 being alined. The bracket is formed with an elongated clear space 31 between its head 23 and its under end; and after the collapsible valve locking members 5 are fusibly connected together, they are inserted between the under end of the valve stem and the upper side of the under bracket end 32, when the bracket head may be screwed into closer relation to the head 10 sprinkler and thereby tightly lock the valve head packing against the valve seat formed on the under end of the supply or coupling pipe 10. After the parts are thus tightly 15 assembled, the set screw 27 is homed to prevent the valve lock carrying bracket from loosening upon the head; and in such tight 20 assemblage, the valve head and the stem are out of such near position to other parts as to make sticking of the valve in consequence 25 of corrosion of opposed metal parts impossible for however long a time the head as a whole is installed, prior to a fire. Melting of 30 the fusible metal causes the valve locking members to collapse under the pressure of 35 water in coupling pipe 10 and on the valve. The collapsible valve locking wings 28 preferably extend horizontally outward of the 40 valve lock carrying bracket; the wings being opposingly recessed at 33 inwardly of the 45 fusible metal 29, and the vertical head extensions 34 of the wings having their 50 opposed ends 35 abutted off a vertical line through the valve stem and bearings 30 which are not only alined one with another 55 but with the axis of the upstanding valve stem. The outlets 2 are formed by outwardly projecting curved walls 2^a extending beyond the main wall of the nozzle or head and open into exterior recesses 2^b having 60 opposed horizontal side walls 2^c, and a bottom wall 2^d. By this construction, the water is 65 better hurled horizontally from the rotating nozzle or distributer head which is shown with four such circumferentially disposed 70 discharge outlets 2, each of which is troughed outwardly of the discharge end of 75 a wall a².

What I claim is:

1. In a rotary distributer head or nozzle 80 provided with water escape openings formed 85

to effect rotation of the head or nozzle by force of water under head flowing through the openings, the combination of an exteriorly flanged supply pipe; anti-friction balls on the flange; a chambered, rotatable, 90 distributor nozzle formed with an interior rib projecting from its inner wall and inclosing a central, valve head receiving opening; the upper, inner margin of the rib being opposed to the ball carrying pipe flange, 95 the nozzle having an annular flange extending upwardly of the rib; the flange being threaded for connection with a ball retaining ring, a ball retaining ring having a center bore inclosing the supply pipe; the valve 100 head being of lesser cross-sectional dimension than the cross-sectional dimension of the valve head receiving opening within the rib for formation of a corrosion preventing clearance between the valve head and the 105 inner wall of said valve head receiving opening, and the valve head having a stem extending outwardly through the nozzle wall for engagement with valve locking means; and valve locking means comprising a collapsible structure having a plurality of 110 parts held disintegrably together by fusible solder.

2. In the combination set forth in claim 1, said discharge openings being formed 115 through said rib and having outlet walls projecting beyond the main wall of the nozzle, such wall being exteriorly recessed at the mouths of the discharge openings to 120 form troughed water escapes. 90

3. A revoluble, chambered distributer head or nozzle provided with water escape 125 openings formed to effect rotation of the head or nozzle by force of water under head flowing through the openings, in combination 130 with a supply pipe having a flanged entrant in said chamber for discharge therein; a bodily movable valve head for the discharge end of the supply pipe; and disintegratable means comprising fusibly soldered members 135 for holding the valve against the discharge end of the pipe until the fusible solder melts, with the valve head out of near contact with 140 all metal except the pipe end; the distributer nozzle being mounted revolvably on the 145 flanged end of the supply pipe. 105

Signed at New York city in the county of New York and State of New York this 10th day of May A. D. 1920.

KARL REZNICEK.
